UNITED STATES PATENT OFFICE.

HAROLD BLUME, OF MORTON, MINNESOTA, AND VERNON GARDNER, OF FAIRVIEW, MONTANA.

PIPE HOLDER.

Application filed April 17, 1926. Serial No. 102,747.

Our present invention has reference to a simple means for effectively locking pipe sections together in an easy, quick and thoroughly efficient manner.

5 A further object is the provision of means for locking a stove pipe section in an opening in a chimney breast and for locking to said section other stove pipe sections which lead directly to the smoke outlet of a stove, 10 furnace or the like.

To the attainment of the above broadly stated objects and others which will appear as the nature of the invention is better understood, the improvement resides in the 15 simple construction, combination and operative association of parts, a satisfactory embodiment of which is illustrated by the accompanying drawings.

In the drawings:

20 Figure 1 is a view illustrating my improvement in applied position, the chimney breast being in section.

Figure 2 is an enlarged sectional view 25 through the elbow pipe member showing the manner in which the pipe sections are secured on the ends thereof.

Figure 3 is a fragmentary perspective view of the metal strap employed.

Figure 4 is a substantial central longitudinal sectional view through the anchor.

Figure 5 is a plan view from which the 30 base element of the anchor is formed.

Figure 6 is a plan view of the removable and adjustable finger which cooperates with 35 the anchor base.

Figure 7 is a perspective view of the anchor complete.

We have shown our improvement in connection with stove pipe sections which lead 40 from a stove or furnace 1 to a chimney flue 2. It is, of course to be understood that we do not wish our invention restricted to a securing and locking means for stove pipe sections, as the same may be used with equal efficiency upon other pipe sections or the like which have interfitting ends. The chimney breast is indicated by the numeral 3 and in the opening that communicates with the flue 2 there is arranged the usual terra cotta 45 sleeve 4. The stove pipe section that is passed through the sleeve 4 is indicated for distinction by the numeral 5. Arranged over the top of the stove pipe section 5 there is a flat plate 6 that provides the base of our improved anchor. In this connection we de-

sire to direct attention to the fact that both our anchoring and securing means are arranged upon the top of the horizontal stove pipe sections and is therefore so positioned as to not attract attention. The plate 6 is bent upon score lines 7 and 8 and is rounded on the score line 9. These elements present an upstanding finger 10 and the outer element of the finger is slotted longitudinally and transversely to provide a 65 spring lip 11. The plate is further bent upon the score line 12 into contact with the outer end of the finger 10, and the edge of the said anchor element 13 is sprung beneath the spring lip 11.

The body plate is slotted longitudinally and transversely, and the metal bounded by these slits is bent outwardly to provide 70 spring lips 14. The body plate 6, adjacent to one of its ends is formed with a transverse opening 15.

The removable and adjustable finger is formed from a single piece of suitable spring metal, as disclosed by Figure 6 of the drawings, the said metal being centrally bent 80 upon itself to provide the contacting and parallel arms of a finger 16. Prior to the bending of the metal, the plate constituting the finger 16 is formed adjacent to its ends with rectangular openings 17, and the said 85 plate in a line with the center of these openings, is bent in opposite directions to provide foot portions 18. The openings 17 are of a size to permit of the sliding of the finger 16 on the base plate 6 and ratcheting 90 over the spring lips, or in reality the spring teeth 14. When the finger 16 is moved to a position to contact with the outer end of the chimney breast or with the outer end of the sleeve 4, the lower portion of the said 95 finger will be frictionally engaged by one of the spring lips or teeth 14, and the contacting engagement of the base 6, as well as the spring fingers or lips 14 with the bore of the sleeve 4, will exert a sufficient 100 friction upon the stove pipe section 5 as to effectively hold one end of the same in the chimney flue.

Through the opening or eye 15 at the outer end of the base plate 6 I secure the 105 eye end 20 of a comparatively thin and narrow spring metal tape 21. This tape is trained along the top of the upper or horizontal stove pipe sections and as disclosed by Figure 2 of the drawings is trained 110

through the outer or horizontal sleeve end 22 of the elbow 23 for the pipe sections. The tape is drawn taut and arranged at an angle in the elbow 23 and has its second end 10 passed between the elbow and the socket end 24 of the upper member 25 of the vertical stove pipe sections. The tape is then trained along the outer side of the vertical line of pipe sections and may have its free end secured to the lower of the vertical pipe sections, although preferably, the end of the tape is rounded or bent upon itself and inserted in the end of the said lower stove pipe section. This bend is contacted by the collar which surrounds the outlet smoke opening in the stove or furnace 1.

The simplicity of our improvement, the cheapness at which it may be constructed and the advantages thereof will, it is believed, be perfectly apparent to those skilled in the art to which such invention relates when the foregoing description has been carefully read in connection with the accompanying drawings. We, of course, do not 25 wish to be restricted to the precise details of construction herein set forth and therefore hold ourselves entitled to make such changes therefrom as fairly fall within the scope of what we claim.

30 Having described the invention, we claim:

The combination with a stove, furnace or the like, chimney and stove pipe sections, including vertical members and an elbow connecting the vertical members with the

horizontal members, the outer stove pipe section of the horizontal members being received through the chimney breast and partly projected into the chimney flue, of an anchor on the last mentioned stove pipe section, including a flat plate bent upon itself 45 adjacent one of its ends to provide an upstanding finger which is formed with a lip, said plate having its end opposite the finger bent angularly and engaged by the lip, said finger designed to contact with the outer wall of the chimney flue, said plate having spaced upstanding yieldable spring teeth, a second finger which has an angle base portion and which is slotted in a line with said base, to receive the plate therethrough and to permit of the second mentioned finger 50 sliding on said plate and being engaged by one of the spring fingers when the said second finger is in contact with the chimney breast, a comparatively thin metal tape connected to the plate and arranged on top of the stove pipe sections, and passed through the socket end of the elbow and directed past the socket end of the vertical stove pipe section received in the elbow and from thence against the remainder of the said 55 vertical stove pipe sections and secured to the lower of said sections.

In testimony whereof we affix our signatures.

HAROLD BLUME.
VERNON GARDNER.
